(57) CLAIM

The ornamental design for a shoe washing bag as shown and described.

DESCRIPTION

FIG. 1 is a front, left, and top perspective view of a shoe washing bag, showing my new design;

FIG. 2 is a rear, right, and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a top plan view thereof of a shoe washing bag of

FIG. 1 shown in an open position.

The portions of the design shown beyond the translucent white shaded area outline in broken lines depict portions of the shoe washing bag that form no part of the claimed design.
